UNITED STATES PATENT OFFICE.

THOMAS H. A. HOWLEY, OF NEW YORK, AND JOHN J. DOOLEY, OF BROOKLYN, NEW YORK.

PLASTER-BOARD.

1,379,444.

Specification of Letters Patent. Patented May 24, 1921.

Application filed October 25, 1919. Serial No. 333,215.

To all whom it may concern:

Be it known that we, THOMAS H. A. HOWLEY, and JOHN J. DOOLEY, both citizens of the United States, and residents, respectively, 5 of the city of New York, borough of Manhattan, in the county and State of New York, and of the city of New York, borough of Brooklyn, in the county of Kings and State of New York, have invented a new and Improved 10 Plaster-Board, of which the following is a full, clear, and exact description.

The object of the invention is to provide a new and improved plaster board arranged to lock or key the plaster in place thus preventing the plaster from becoming accidentally detached, even should the plaster board or the plaster become moist and soft.

Another object is to reinforce the plaster board and at the same time provide a simple 20 means for nailing it to the studding, joists or other support without danger of the nail heads pulling through the board in case the latter becomes damp and soft.

Another object is to render the plaster board exceedingly strong by the use of the reinforcement and the locking keys with a view to sustain heavy plaster, cornices, or other ornaments and the like.

With these and other objects in view, the 30 invention consists of certain novel features of construction as hereinafter shown and described and specifically pointed out in the claims.

A practical embodiment of the invention 35 is represented in the accompanying drawings forming a part of this specification, in which similar characters of reference indicate corresponding parts in all the views.

Figure 1 is a fragmentary face view of 40 the improved plaster board;

Fig. 2 is a sectional plan view of the same on the line 2—2 of Fig. 1;

Fig. 3 is a face view of the improved 45 plaster board as applied; and

Fig. 4 is a sectional plan view of the same on the line 4—4 of Fig. 3.

The body 10 of the plaster board is formed in the usual manner of alternating layers made of paper and a filler, preferably of a 50 cementitious material. In order to reinforce the body 10 and to provide a means for securely fastening the plaster board to the studding of a wall or the joists of a ceiling or to any other suitable support 11 (see 55 Fig. 4) use is made of metallic strips 12 embedded in the body 10 during the process

of its manufacture. In practice, about three such metallic strips are embedded in an ordinary-sized plaster board of say 3 x 8 feet, and the said strips are arranged parallel 60 one relatively to the other and are spaced apart about a foot, according to the spacing of the studs or other support 11. The strips 12 are preferably embedded within the body 10 adjacent the front layer, as indicated in 65 Figs. 2 and 4, but we do not limit ourselves to this particular arrangement. It will be noticed that by the arrangement described the plaster board can be readily and securely fastened in position on the support 11 by 70 the use of nails 13 driven through the plaster board and the strips 12. It will be noticed that the strips 12 reinforce the body 10 and at the same time provide a simple means for securely nailing the plaster board to the 75 support without danger of the nail head pulling through the board in case the latter becomes damp or soft.

In order to further reinforce the plaster board and to provide a keying means for 80 holding the plaster 14 securely in position on the outer face of the plaster board, the following arrangement is made: The body 10 is provided intermediate the strips 12 and between the strips and the ends of the 85 board with punctures 20 arranged in spaced and staggered relation, preferably as indicated in Figs. 1 and 3, and the punctures 20 define locking tongues or keys 21 integral with the body 10 and normally flush with 90 the faces of the plaster board. It will be noticed that by this arrangement the punctures 20 are normally closed by the tongues 21 but when the plaster 14 in its plastic state is applied to the face of the plaster 95 board then the plaster exerts a rearward pressure against the tongues 21 and thus swings the same rearward into an angular position relative to the rear face of the body 10, as plainly indicated in Fig. 4. It 100 will be noticed that a portion of the plaster 14 passes through the keyway formed by the bending of the tongues 21 and engages the rear face of the body 10 adjacent the puncture 20 and also engages the sides and the 105 free ends of the now struck-up tongues 21 as well as the rear margins thereof thereby 110 securely keying the plaster in position on the plaster board. The plaster also fills the openings made by the rearward bending of the tongues 21, as shown in Fig. 4.

By the combined action of the reinforce-

ing strips 12 and the tongues 21, the plaster board is capable successfully to sustain heavy plaster and especially cornices and heavy ornaments.

5 It will further be noticed that the plaster is not liable to become accidentally detached even should the plaster board or the plaster become moist or soft.

Having thus described our invention, we 10 claim as new and desire to secure by Letters Patent:—

1. A plaster board provided with slits in spaced relation and forming tongues, the slits extending through the board and the 15 tongues being normally flush with the faces of the plaster board and lying within the openings defined by the slits, the tongues moving into an angular position on the back of the plaster board on applying plaster to

the face thereof, each of the said tongues on 20 assuming an angular position forming a keyway in the corresponding opening, the wall of each opening forming with the edge of the corresponding angular tongue a locking means for the plaster passing through 25 the opening onto the back of the plaster board and onto the edge of the tongue.

2. A plaster board, comprising a body having a plurality of superposed layers and a plurality of spaced nailing and reinforcing strips embedded in the said body. 30

3. A plaster board, comprising a body having a plurality of superposed layers and a plurality of spaced nailing and reinforcing strips embedded in the said body adjacent the front layer. 35
